CLOSING FLAP FOR ENVELOPES AND
THE LIKE

Edward Joseph Malo, Benton Harbor, Mich.

Application May 23, 1945, Serial No. 595,321

1 Claim. (Cl. 229—80)

1 This invention relates to an improved envelope or equivalent mailing article, in which both body and flap are provided with especially constructed coinciding gummed areas, these of such nature and form as to avoid inadvertent self-sealing, a result which so often occurs in tropical climates and areas.

More specifically, I attain the objects sought by corrugating the gummed sealing edge of the closing flap and, secondly, corrugating the coacting and coinciding "stick down surface" of the body, the corrugations of the respective areas meshing and adhering in a pre-determined manner.

Using coinciding corrugated companion areas on the flap and body respectively and then applying adhesive coatings on alternating and longitudinally spaced positions, I have found it possible to produce an envelope in which the parts will not accidentally adhere prior to the regular hand sealing stage.

Other features and advantages will become more readily apparent from the following description and the accompanying illustrative drawing.

In the drawing:

Figure 1 is a top plan view of a conventional letter type or equivalent envelope with its portions constructed in accordance with the principles of the present invention.

Figure 2 is an enlarged fragmentary sectional view taken approximately on the plane of the line 2—2 of Figure 1.

Figure 3 is a fragmentary section through the envelope after the flap has been folded down and pressed and sealed in its closing position.

Referring to the drawings by distinguishing reference numerals, it will be seen that the body of the envelope is indicated at 4 and is, for the main, of conventional construction and form. The flap 5 joins the open mouth by the usual fold line 6. The flap is also of conventional configuration. The marginal somewhat V-shaped gum-coated surface 7 differs from the regular envelope in that is corrugated substantially from end to end. The corrugations may be described as comprising alternate flutes 8 and 9 respectively. The attaching surfaces of the flutes 8 are gum-coated, whereas intervening flutes 9 are non-coated.

The coinciding and therefore, complementary flap receiving and anchoring area 10 on the body

2 of the envelope is likewise, corrugated. Here the corrugations are differentiated by the numerals 8a and 9a respectively. It will be noted from the drawings that the corrugations again define flutes and these are alternated insofar as the gummed and non-gummed surfaces are concerned. Also, it will be observed that the flutes on the flap 7 alternate or are staggered in respect to the coacting ones on the body area 10. Or, to put it otherwise, the gummed flutes 8 on the flap seat in the non-gummed flutes 8a, while the gummed flutes 9a on the area 10 register with the non-gummed flutes 9 on the flap 7.

It is to be understood that the flutes formed thereby form a shallow hill-and-dale companion seals and that the flutes can be either rectangular or semi-circular or of other cross-sectional forms.

As a safeguard the flap 7 can be tucked into the body at the time of manufacture and packaging. However, this is not essential in an envelope of the construction shown because it is believed that despite tropical climatic moisture conditions, the coacting surfaces on the flap and body will not adhere, that is permanently adhere, until they are actually pressed together firmly by hand. I have found that in tropical zones certain types of adhesive surfaces will cause the flaps to inadvertently seal themselves against the bodies of the envelopes. This makes a condition inconvenient and difficult for the user. On the other hand, the use of the corrugated areas 7 and 10 with the especially gummed alternating and staggered flutes wholly overcomes the objection pointed out and at the same time makes for the provision of an envelope which is aptly fitted for the particular purposes intended.

It is thought that persons skilled in the art to which the invention relates will be able to obtain a clear understanding of the invention after considering the description in connection with the drawings. Therefore, a more lengthy description is regarded as unnecessary.

Minor changes in the shape, size and arrangement of details coming within the field of invention claimed may be resorted to in actual practice, if desired.

I claim:

An envelope of the class described comprising a body and closing flap therefor, the outer marginal edge portion of said flap being corrugated,

the corrugations defining flutes, the flutes being alternately gummed and plain, the wall of the body with which said fluted area coats also being corrugated, the latter corrugations matching corrugations on the flap, the corrugations on the body defining flutes and said flutes being alternately gummed and plain, and the respective flutes on the body and flap being staggered in relation to the placement of the gummed and plain flutes, in the manner and for the purposes 10 described.
